LIQUID SOAP CONTAINER

Filed Jan. 23, 1931

FIG. 1.

FIG. 2.

Inventor
Audrey E. Westwood
by Wilkinson & Wilkinson
Attorneys

UNITED STATES PATENT OFFICE

AUBREY EDMUND WESTWOOD, OF WOOTTON WAWEN, ENGLAND

LIQUID SOAP CONTAINER

Application filed January 23, 1931, Serial No. 510,802, and in Great Britain February 4, 1930.

This invention relates to containers for liquid soap and has for its object the provision of means whereby the definite discharge of a sufficient quantity of soap is obtained 5 with a minimum of effort. A further object is the prevention of leakage when the container is not in use.

In my patent specification No. 1,742,676 there is described an oil can which is provided 10 with an internal pumping mechanism consisting of a hollow piston and cylinder fitted with valves and internal return springs, the said cylinder working upwardly over the piston and being moved and controlled by a 15 lever on the outside of the can.

In the present invention the above described mechanism is adapted for use with a container for liquid soap and the invention therefore comprises a container for liquid 20 soap in which depression of an operating lever effects the discharge of a sufficient quantity of soap, the latter being brought into position for discharge by means of an internal pumping mechanism consisting of a 25 hollow piston and cylinder fitted with valves and internal return springs, the said cylinder working upwardly over the piston and being connected with the operating lever, the major portion of which, or at least the end thereof 30 which is connected to the pumping mechanism, is within said container.

For retaining the liquid soap in position for discharge and preventing leakage when the container is not in use the outlet orifice 35 through which the soap is discharged is provided with a valve by means of which the outlet orifice is closed when the device is not in use.

A preferred construction of the device according 40 to the invention is shown in the accompanying drawings in which:—

Fig. 1 is a vertical sectional view of the container, certain of the parts being shown in elevation;

45 Figs. 2 and 3 are part-sectional views of the upper part of the container showing modifications in the position and construction of the operating lever.

Referring first to Fig. 1; the container comprises 50 a body 4, which may be of any suitable

shape but is preferably of such cross section that one side thereof is substantially flat so that the container may be affixed to a wall or the like by means of a flat strip or bracket 5 attached to the body, and the latter is provided with a tightly fitting lid 6 which is removable for filling the container or inspection or removal of the operating mechanism.

The pumping mechanism, which is entirely separate from the body and may easily be 60 detached therefrom, consists of a head 7 to which is attached a hollow piston 8 on which is slidably mounted a movable cylinder 9. The piston is of uniform diameter throughout its length and both piston and cylinder 65 are provided with internal return springs and ball valves and in construction and operation are exactly as described in the aforementioned specification. As shown in the present construction the cylinder is provided 70 on its outside with a slotted lug 10 in which is inserted the thinned portion of a rod 11 the upper end of which passes through a slot in one end of the operating lever 12 and is enlarged, as at 13, to form a bearing surface 75 on which the end of the lever 12 acts. This lever, the major portion of which is within the casing, is provided at its other end with a knob 14 and is bent upwards to pass through a suitable slot 15 in the lid of the container. The lower part of the lever, extending from the slotted end to the point 16 at which it is bent upwards, is as shown, normally horizontal and rests on the top of the head 7. On 80 depressing the knob 14 the lever turns about the point 16 as a fulcrum, the slotted end is raised and the cylinder drawn upwards against the action of its internal return spring. On release of the lever the cylinder 85 is returned to its initial position by its return spring, this action bringing the lever back to normal position.

The head 7 is bored internally to provide a communicating passage between the inside of the hollow piston 8 and a discharge tube 95 17 which is attached to the head and is of such length that it extends beyond the bottom of the container when the pumping mechanism is in position inside the container. The discharge tube 17 is provided at its lower 100

end with a conical seating 18 for a non-return needle valve 19 which is held closed by means of a spring 20 bearing against an internal shoulder on the delivery nozzle 21. 5 This nozzle 21 is screwed on to the end of the tube 17 and also serves to retain the mechanism in position as hereinafter described.

The body is provided internally with a socket 22 adapted to receive a stud or lug 23 on the end of the head remote from the discharge tube. On the other side of the container, opposite to the socket 22, is provided an open-ended tube 24 through which passes the discharge tube 17. The tube 24 is sealed 15 into the bottom of the container and it is of such a length that when the pumping mechanism is in position the underside of the head just rests on the upper end of the tube. The socket 22 and tube 24 serve to position the 20 internal mechanism correctly and are preferably arranged so that the latter is located approximately at the centre of the container, the bottom of which is curved downwardly from either end towards the centre, in a direction transverse to the plane of the section in Fig. 1, so that when the level of liquid in the container is near the bottom there is 25 always sufficient to cover the end of the pump cylinder. When the mechanism is in position the lug 23 fits into socket 22 and the discharge tube 17 extends through the tube 24, projecting beyond the lower end of the latter as above described. The nozzle 21 is screwed on the end of the tube 17 until 30 it abuts against the lower end of tube 24 thus holding the internal mechanism firmly in position. To take out the mechanism it is only necessary to remove the lid and the nozzle 21 when the whole mechanism can 35 be removed bodily by an upward pull.

The operation of the device is as follows. Assuming that the container is filled with liquid and the mechanism is in position, on 40 depressing the knob 14 the cylinder is moved upwardly over the piston and a certain quantity of liquid is forced into the head 7 and the discharge tube 17. The liquid will not immediately be ejected however, due to the action of the valve 19. This valve will not 45 open until the pressure of liquid is sufficient to overcome the action of the spring 20 and this pressure will usually not be sufficient until two or three initial strokes of the pump have been made. When the liquid pressure 50 reaches a point at which it nearly overcomes the force of the spring the next stroke of the pump will cause the liquid already in the tube to be ejected in a steady stream which ceases immediately on completion of the pump 55 stroke the outlet orifice being positively closed by the valve 19. Once the head and tube have been initially filled, however, each depression of the knob 14 (i. e. each pump stroke) will cause the liquid which was 60 forced into the tube 17 by the previous stroke 65 of the pump to be ejected through the nozzle. The valve 19 also prevents leakage of any liquid by closing the outlet orifice when the device is not in use.

In Fig. 2 is shown a similar arrangement 70 in which the lever is arranged so that the knob 14 has to be pushed inwards towards the container to operate the device. In this case the lever 12, instead of being fulcrumed on the head 7, is fulcrumed on the lower edge 75 of the slot through which it passes, this edge being actually the top edge of the body 4.

In Fig. 3 the arrangement is shown for actuation from the top of the container; the knob 14 is not provided on the end of the 80 lever itself but is attached to the top of a rod 25 which slides in a tubular bearing 26, the other end of the rod bearing on the lever to cause pivoting of the latter when the knob is depressed. 85

What I claim as my invention and desire to secure by Letters Patent is:—

1. A device for ejecting a predetermined quantity of liquid, such as liquid soap, comprising in combination a container consisting of a body portion and a lid portion; pumping mechanism arranged internally of said body portion, said pumping mechanism comprising a hollow head, a communicating hollow piston fixed thereon, a cylinder working over said piston, ball valves in said piston and said cylinder and a return spring inside said cylinder; an operating lever fulcrumed on said head and projecting through said lid; a rod connecting the inner end of said lever and said cylinder; a discharge pipe projecting downwardly from said head through the bottom of the container; a tube secured to said container and surrounding said discharge pipe; a nozzle on the outer end of said pipe and a non-return valve within said nozzle which normally closes the end of said discharge pipe. 100

2. A device for ejecting a predetermined quantity of liquid, such as liquid soap, comprising in combination a container consisting of a body portion and a lid portion; pumping mechanism arranged internally of said body portion; said pumping mechanism comprising an elongated hollow head, a communicating hollow piston fixed thereon, a cylinder working over said piston, ball valves in said piston and said cylinder and a return spring inside said cylinder; said pumping mechanism being entirely separate from the body of the container and removable therefrom; an operating lever fulcrumed on said head and projecting through said lid; a rod connecting the inner end of said lever and said cylinder; a lug on one end of said head; a socket on the body portion of said container to receive said lug; a discharge pipe extending downwardly from the other end of said head and projecting through the bottom of 110 115 120 125 130

the container; a tube attached to the body of said container to receive said discharge pipe; a nozzle screwed on the projecting end of said discharge pipe so that upon removal of said 5 nozzle the whole of the pumping mechanism and said discharge pipe may be removed from said container; and a spring-biased non-return valve within said nozzle normally closing the end of said discharge pipe.
